CLAIM

The ornamental design for a swim platform cover for a boat, as shown and described.

DESCRIPTION

FIG. 1 is a right perspective view of a swim platform cover for a boat showing my new design, the swim platform being in a closed configuration;

FIG. 2 is a perspective view from the left rearward side of the swim platform cover for a boat shown in FIG. 1 in a slightly opened position;

FIG. 3 is a perspective view from the left rearward side of the swim platform cover for a boat shown in FIG. 1 in a partially opened position;

FIG. 4 is a perspective view from the left front side of the swim platform cover for a boat shown in FIG. 3;

FIG. 5 is an enlarged right side view of the swim platform cover for a boat shown in FIG. 1 in an almost fully open position;

FIG. 6 is an enlarged perspective view from the right rearward side of the swim platform cover for a boat shown in FIG. 1 in a fully opened position; and,

FIG. 7 is a right side view of the swim platform cover for a boat in FIG. 6.

The broken line illustrations in the drawing figures of the boat, ladder, and support arm are for illustrative purposes only and form no part of the claimed design.
